CLAIM

The ornamental design for a fluid transfer lid, substantially as shown and described.

DESCRIPTION

FIG. 1 is a first perspective view of a fluid transfer lid showing our new design.

FIG. 2 is a second perspective view of the fluid transfer lid shown in FIG. 1.

FIG. 3 is a first end view of the fluid transfer lid shown in FIG. 1.

FIG. 4 is a second end view of the fluid transfer lid shown in FIG. 1.

FIG. 5 is a front view of the fluid transfer lid shown in FIG. 1 (the back view being a mirror image thereof).

FIG. 6 is a top view of the fluid transfer lid shown in FIG. 1.

FIG. 7 is a bottom view of the fluid transfer lid shown in FIG. 1; and,

FIG. 8 is a cross-sectional view along the longitudinal axis of the fluid transfer lid shown in FIG. 1.

The broken lines show portions of the design that form no part of the claimed design.

1 Claim, 3 Drawing Sheets
